UNITED STATES PATENT OFFICE.

FRED WRIGHT, OF NORTH CHICAGO, ILLINOIS, ASSIGNOR, BY MESNE ASSIGNMENTS, TO STANDARD CONVEYOR COMPANY, OF NORTH ST. PAUL, MINNESOTA, A CORPORATION OF MINNESOTA.

HOISTING MACHINE.

Application filed January 3, 1922. Serial No. 526,609.

To all whom it may concern:

Be it known that I, FRED WRIGHT, a citizen of the United States, residing at North Chicago, in the county of Lake and State of Illinois, have invented a certain new and useful Improvement in Hoisting Machines, of which the following is a full, clear, concise, and exact description, reference being had to the accompanying drawings, forming a part of this specification.

My invention relates to conveying machinery, and more particularly, to an improved hoisting machine, especially adapted for stacking or tiering barrels, boxes, packages, and the like.

In large commercial establishments, for example, and particularly in establishments devoted to the packing, shipping, storing or handling of barrels, boxes, packages of goods, and the like, it is a matter of material importance to provide for quickly and efficiently handling the goods and for piling or stacking the same in tiers in order to secure and utilize all of the space possible. While various machines have been provided for this purpose, the difficulties encountered and manual labor necessary, in connection with their operation are well known.

It is an object of my invention to provide a novel, simple and improved machine for stacking or tiering the goods expeditiously and with a minimum amount of manual labor. One of the provisions to this end is an improved power driven machine having an improved system of control. Another provision to the same end is an improved loading mechanism for automatically loading the goods upon the movable carrier of the machine. A further feature is the provision of an improved load carrying platform adapted for rotation about a vertical axis to receive or deliver the load at any desired angle, and a still further provision is an improved braking mechanism for automatically arresting the movement of the movable carrier of the machine when the motor or other source of driving power is cut off.

In carrying out the above, I employ a motor suitable for automatic control for operating the movable carrier of the machine, and I control the motor by the move-

ment of the carrier, so that when the carrier is elevated to the desired point, the motor will be automatically cut off. The braking mechanism provided is automatically brought into operation at this point to positively arrest further movement of the carrier which frequently occurs due to the momentum of the load and the over-run permitted in the usual electric motor. When the carrier is lowered or permitted to descend to the desired point, the motor is again automatically cut off and the braking mechanism again brought into operation to positively arrest movement of the carrier. A driving connection is provided between the motor and the loading mechanism, and this connection is so controlled by the movement of the carrier that when the carrier reaches the proper position, the loading mechanism operates to deliver the load thereto. As the load is raised, the driving connection between the motor and loading mechanism is maintained in engagement until the loading mechanism is properly reset to receive another load and is then released until the carrier again approaches the position in which another package or load is to be delivered thereto.

A further object of my invention is the provision of a machine of the class described, which is simple, inexpensive and superior in construction, simple, effective, safe and reliable in operation and economically maintained.

A further provision of my invention is an improved safety device adapted to be automatically brought into operation to prevent a sudden descent or uncontrolled dropping of the carrier in the event the carrier operating cable breaks, or other part fails.

Further objects and advantages will appear from the following detailed description and the claims taken with an inspection of the accompanying drawings, in which:

Figure 1 is a perspective view of a machine embodying my invention;

Fig. 2 is a rear end view of a machine embodying the controlling system of the invention;

Fig. 3 is a side elevational view of the same;

Fig. 4 is a diagrammatic layout of the arrangement for controlling the motor, and applying the braking mechanism;

Fig. 5 is a perspective view of the load carrying platform;

Fig. 6 is a fragmentary perspective view of the mechanism for controlling the driving connection between the motor and loading mechanism;

Fig. 7 is a fragmentary front elevational view of the carrier frame showing a safety appliance for preventing sudden descent or uncontrolled dropping of the carrier; and

Fig. 8 is a side elevational view of the same.

With reference now to the drawings, the frame of the particular embodiment of the invention selected for illustration comprises a base 5, preferably of angle iron and rectangular formation. One end of the base 5 is provided with a pair of supporting feet 6. The opposite end is supported by suitable rollers 7. Journaled between the opposite sides at the rear end of the machine in a bearing 8 is a caster or roller 9. The bearing 8 is pivoted to the frame and provided with a handle 10. Normally, the feet 6 rest upon the floor, with the caster 9 raised slightly therefrom. When the handle is lowered, the caster 9 is swung into engagement with the floor, raising the feet 6 so that the machine may be transported to any desired place.

A pair of standards 11 mounted in upright position, between the opposite ends of the base 5 form an upright guide frame, up and down which a carrier 12 is adapted for movement. The standards 11 are preferably constructed of channel iron arranged with their inner channeled faces facing inwardly to receive the guide rollers or other cooperating portions of the carrier frame, usually arranged to travel therein. The upper ends of the standards 11 are connected by a transversely arranged strut 13. Within their lengths, these members are braced by suitable bracing struts 14, arranged diagonally therebetween. The standards 11 may be made up in sections pivotally connected through plates 15, as shown, if so desired, so that the upper portion of the guide frame may be folded or swung back and secured. The details of the frame work so far described do not necessarily enter into the present invention, and may be varied in so far as the essence of the invention is concerned.

The carrier frame 12 is provided at its lower end with a pair of horizontally extending arms 16. These arms 16 carry a circular track 17 about which a plurality of anti-friction rollers 18 carried by the platform 19 are adapted to travel. The platform 19 not only moves with the carrier frame 12, but is mounted for rotation about

an axial stud 20, the upper end of which may be headed to hold the rollers 18 carried thereby in proper cooperation with the track 17. The platform 19 is provided with a pair of rigid upright posts 21 and a pair of yieldable studs 22 normally projected from the upper surface of the platform by coiled springs 23 arranged between the platform and heads 24 at the outer ends of these studs as shown in Fig. 5. When a barrel 25, for example, is loaded upon the platform, as will be hereinafter described, the yieldable studs 22 serve as a cushion for taking the load, which then rolls over against the rigid posts 21. The posts 21, the upper ends of which are finished to conform to the periphery of the barrel 25 serve as stops which, with the studs 22, which are thereupon sprung up into engagement with the opposite side of the barrel effectively hold the same against displacement from the platform during the hoisting operation. When the barrel is elevated to the desired position, it may be delivered from the platform on to a pile, stack or conveyer at any desired angle simply by rotating the platform about the stud or post 20 to the desired position.

The transverse strut 13 carries a bracket member 26 in which one end of a vertical post 27 is journaled for rotation. The opposite end of the post 27 is journaled in a bearing carried by a channel iron 28 arranged transversely across the standards 11. Within its length the post 27 carries a pin or axle 29, upon which a pulley or sheave 30 is mounted for rotation.

Over this sheave or pulley 30 operates a cable, rope or the like 31, one end of which is secured to the movable carrier frame 12. The opposite ends of the cable 31, after passing upwardly from the frame 12 and over the sheave 30, passes down and is secured to a winding drum or windlass 32, the shaft 33 of which is journaled in bearings 34 secured to upright channels 35 and 36, mounted in position between the opposite sides of the base 5, the channel 36 at the rear end of the base and the channel 35 between the standards 11. The channels 35 and 36 are secured at their upper ends to transversely arranged frame members 37 across which a pair of longitudinally arranged motor carrying channels 38 are secured.

The motor 40 is connected through a chain 41 with a sprocket wheel 42 mounted upon a transversely arranged shaft 43 journaled in the framing of the machine. Connection between the motor and shaft 43 may, of course, be through cooperating gears instead of the chain 41, or in any other desired manner. The shaft 43 carries a worm 44 which meshes with and drives a gear wheel 45 mounted upon the winding drum or windlass shaft 33, so that upon starting the motor, the drum 32 will be rotated either in

a direction to effect a coiling or winding up the cable 31 thereupon and a consequent raising of the platform 19, or in a direction to permit unwinding of the cable therefrom and a consequent lowering of the platform.

The motor 40 is connected to the necessary feed wires through leads 48 and to a controller 49 through leads 50. The controller 49 is provided with an operating arm 51 having a handle 52 at one end and connected at its opposite end with the free ends of a continuous cable, rope or the like 53. One end of the cable 53 is secured to the inner end of the arm 51. The cable after passing up over a sheave 54 mounted upon one of the standards 11 passes down and is provided within its length with a short length of chain 55 trained over a sprocket wheel 56 mounted at the lower end of the standard 11. The opposite end of the cable 53 extends up and is secured to the inner end of the arm 51. The movable carrier frame 12 is provided with an eye or lug 65 through which the length 58 of the cable 53 extends or at any rate, a lug carried by the movable frame 12 moves up and down along the cable length 58 for cooperation with stops or enlarged links 60 and 61 at the opposite ends thereof for a purpose which will be hereinafter apparent. The stops are preferably secured in place by suitable set screws 62 or the like, so that their position may be quickly and conveniently adjusted or changed.

The controller arm 51 has three positions, i. e. an off position, an up position into which it is moved to run the motor 40 in a direction to wind the cable 31 upon the drum 32 to raise the platform 19 and a down position into which it is moved to run the motor in the opposite direction to permit unwinding of the cable from the drum with a consequent lowering of the platform or carrier frame. It will now be apparent that by swinging the arm 51 into the up position, the motor 40 will be started and the platform or carrier raised or moved upwardly until the lug 65 engages the stop 60 whereupon the arm 51 will be automatically returned to the off position through the cable 53 and the motor stopped. Upon delivering the goods from the carrier, the arm 51 is swung into the down position whereupon the motor is started and the platform or carrier permitted to descend until the lug 65 engages the stop 61 whereupon the arm 51 is automatically returned to the off position and the motor stopped. As already pointed out, the stops 60 and 61 are adjustable so that the motor may be automatically stopped at any desired point in the movement of the carrier.

To bring the carrier 12 to rest and prevent overrunning thereof, when the motor 40 is stopped or spinning of the worm shaft due

to the inertia of the motor, I provide a brake mechanism which is automatically brought into action by the movement of the carrier. This mechanism comprises a drum 70 mounted upon one end of the shaft 43 and a co-operating brake band 71 by means of which the desired braking effort is applied thereto. One end of the brake band 71 is connected to an arm or link 72 (Fig. 4), the opposite end of which link is connected to an arm 73 pivoted within its length as at 74 and connected at its opposite end to a block or link 75. The opposite end of the band 71 is connected to one end of the link 75, the opposite end of which link is connected with an arm 76, pivoted eccentrically at its opposite end to a disc 77 carried by the sprocket wheel 56 for rotation therewith.

It will now be apparent that when the arm 51 is moved into the down position for example that the sprocket wheel 56 is rotated through the chain 55, moving the arm 76 through its eccentric connection with the disc 77 into the position shown in dotted lines. This movement of the arm 76 expands the band 71 from engagement with the drum 70 by pulling the end connected with the link 75 into the position shown in dotted lines and at the same time, swinging the arm 73 about its pivot 74 to push or force the opposite end of the band into the position shown in dotted lines. Upon descent of the carrier to the desired point, engagement with the stop 61 not only stops the motor 40, but at the same time, turns the sprocket wheel 56 in a clockwise direction to swing the arms 76 and 73 back into the positions shown in full lines, contracting the brake band into braking engagement with the drum 70 and arresting further movement of the carrier.

When the arm 51 is moved into the up position, the arm 76 is moved in a clockwise direction from its normal horizontal position to expand the band 71 from engagement with the drum or wheel 70. Engagement with the stop 60 upon movement of the carrier to the desired elevation stops the motor and contracts the band into braking engagement with the drum or wheel 70.

Coming now to the loading mechanism with which the machine shown in Fig. 1 is equipped, the end of the shaft 43 is provided with a bevel gear 80 fixedly mounted thereupon. The bevel gear 80 meshes with a bevel gear 81 loosely mounted upon a shaft 82 mounted lengthwise along one side of the machine in suitable bearing brackets 83. A sleeve or collar 84 splined for rotation with the shaft 82 and adapted to be shifted longitudinally therealong is provided with a clutch face 85 adapted for clutching engagement with a cooperating portion of the bevel gear 81 to connect the gear 81 and sleeve 84 for rotation together.

The sleeve or collar 84 is shifted along the shaft 82 through a lever arm 86 pivoted at 100 and provided with a forked lower end embracing the collar and carrying suitable pins which extend into a circumferential groove therein. The upper end of the lever 86 is provided with a handle portion 87. Adjacent the handle portion 87, the lever is connected through a link 88 with an arm 89 mounted upon a short shaft 90 (Fig. 6) journaled in a bearing 91 carried by the frame of the machine. The shaft 90 carries a roller carrying arm 92 having a shoe member 94 secured to the carrier 12 for movement therewith. The lower end of the shoe member 94 is curved outwardly as shown at 95.

An arm 96 pivotally connected to the lever 86 at one end extends forwardly through a bracket member 97 carried by the frame of the machine. A spring 98 coiled about the arm 96 between the bracket 97 and a collar 99 carried by the arm tends to force the arm 96 rearwardly and thereby the lever 86 about its pivot 100 in a clockwise direction to disengage the sleeve 84 from the gear 81. Engagement of the shoe 94 with the roller 93 moves the link 88 forwardly through the arm 89 swinging the lever 96 in a counterclockwise direction about its pivot 100, and the clutch base of the sleeve 84 into clutching or driving engagement with the cooperating space of the gear 81.

The forward end of the shaft 82 is externally threaded as shown at 101. This externally threaded portion 101 engages in an internally threaded stud 102 adjustably mounted in a length of channel iron 103 adjustably secured upon an arm 104 pivoted at 105 to the frame 5. A link 106 connected at one end with the arm 104 extends forwardly and is connected at its opposite end to an arm 107 fixed upon a shaft 108 arranged transversely across the front of the base 5, so that the shaft 108 will be rotated by movement of the arm 104 about its pivot 105. Secured upon each of the opposite ends of the shaft 108 for rotation therewith is a loading arm 110. These arms 110 are provided with gradually inclined upper running surfaces 111, which surfaces terminate in barrel or load receiving depressions 112 adjacent the inner ends of the arms.

Assuming that the loading arms 110 are in the position shown in dotted lines in Fig. 1 and that the platform or carrier has been raised or elevated to the desired position and the load delivered therefrom, the operation of the machine is as follows:

The controller arm 51 is moved from the off position (Fig. 4) into which it is automatically moved when the desired elevation is reached as already pointed out, into the

down position starting the motor 40 in the direction to permit unwinding of the cable 31 with a consequent lowering of the carrier frame 12 and the platform 19 carried thereby. During this movement of the carrier, the shoe 94 comes into engagement with the roller 93 swinging the lever 86 in a counterclockwise direction about its pivot 100 against the tension of the spring 98. This movement of the lever 86 moves the clutch face of the sleeve 84 into driving engagement with the cooperating clutch face of the gear 81. The rotation of the shaft 82 thereupon sets up swings the lever 84 in a counterclockwise direction about its pivot 105 through the threaded engagement with the stud 102.

The arms 110 up the gradual inclines of which the barrel 25 has been rolled into the depressions 112 are thereupon swung upwardly lifting the barrel 25. During this time, the platform 19 is moving into position to receive the barrel and upon reaching such position, the barrel is loaded or delivered by the arms 110 thereto, yieldable studs 22 serving as a cushion for receiving the barrel which thereupon rolls over between the pairs of studs 22 and posts 21 and is thereby maintained against displacement. When the lowermost position of the carrier is reached, the motor is stopped and the brake applied as already described.

To elevate or hoist the barrel to the desired position, the controller arm is then moved into up position, starting the motor 40 in the direction to wind the cable 31 and thereby raise the platform. The shoe 94 continuing in engagement with the roller 93 during the initial upward movement of the carrier causes rotation of the shaft 82 in the opposite direction, thereby returning the loading arms 110 into their dotted line positions to receive another barrel which is then placed thereupon. Upon returning the arms 110 to such position, the shoe 94 is moved out of engagement with the roller 93 whereupon the lever 86 is swung about its pivot 100 in a clockwise direction by the spring 98 to disengage the clutch through which the loader mechanism is driven. Upon reaching the desired elevation, the motor is automatically stopped and the brake automatically applied. The barrel may be then delivered from the machine at any desired angle simply by rotating the platform 19 about the studs or posts 20.

To prevent a sudden descent or uncontrolled dropping of the carrier in the event of the breaking of the cable 31 or failure of another part of the machine, I provide a safety device comprising a shaft 120 (Figs. 7 and 8) mounted transversely across the carrier frame 12 in bearings 121. The end 122 of the cable 31 is connected to one arm of a bell crank lever 123 fixed upon the

shaft 120 intermediate its opposite ends. A coiled spring 124 secured at one end to the other arm of the bell crank lever 123 extends and is secured at its opposite end to a frame member 125 of the carrier frame 12. The opposite ends of the shaft 120 carry cams 126 having serrated edges 127 adapted for engagement with the upright standards 11 along which the frame 12 is movable.

10 It is believed that the operation of the safety appliance is obvious. In the event the cable 31 breaks, for example, the shaft 120 will be rotated by the spring 124 and the serrated edges 127 of the cams 126 carried thereby, forced into secure engagement with the upright standards 11 and the carrier checked against further descent until the necessary repair is made. It should be noted that when the serrated edges of the cams 126 are forced into engagement with the uprights 11 by the spring 124 any tendency toward further descent of the carrier 12 will increase the secureness of this engagement, and thereby positively hold the carrier against dropping.

I conducted tests and find that with a machine embodying the features of my invention, exceedingly heavy loads, barrels of oil weighing from five to six hundred pounds, for example, may be handled expeditiously and with a minimum of manual labor.

While I have described my invention in connection with the details of particular embodiment, I do not intend thereby to limit the invention to such details, as I am aware and contemplate that modification and changes may be made in adapting the invention for use under various conditions and in different relations without departing from the essential aspect of the invention, and I have drawn the appended claims accordingly. For example, embodying the principle of the loading mechanism in a device for delivering the goods from the machine when the desired elevation is reached is contemplated.

I claim:

1. In combination, a load carrying surface, a pair of rigid stop members projecting from said surface and adapted for cooperation with one side of the load, a pair of yieldable studs for receiving the load upon delivery of the same to said surface, said studs being thereafter projected into engagement with the opposite side of the load to hold the same against displacement.

2. In a machine of the class described, a guide frame, a carrier movable therealong, a swinging cam connected with the carrier and adapted for cooperation with said guide frame to lock the carrier against movement, spring means for swinging said cam into cooperation with the guide frame and means connected with the carrier for moving the same, said means normally restraining said

spring means and thereby the swinging cam out of engagement with the guide frame.

3. In a machine of the class described, a guide frame, a carrier movable therealong, a rotatable shaft carried by the carrier, a cam on said shaft adapted for cooperation with the guide frame to lock the carrier against movement, a bell crank on said shaft, a coiled spring connected with one arm of said bell crank to swing the cam into cooperation with the guide frame, a cable connected with the other arm of said bell crank to move the carrier, said cable normally restraining said spring and thereby the cam out of engagement with the guide frame.

4. In a machine of the class described, a vertically movable carrier, a driving motor therefor, a threaded shaft adapted for driving connection with said motor and means for delivering a load to the carrier, said loading means being connected with said shaft through an internally threaded member cooperable with the threaded portion of the shaft.

5. In a machine of the class described, a vertically movable carrier, a driving motor rotatable in one direction to raise said carrier and in the opposite direction to permit descension of the carrier, a shoe member carried by the carrier, a threaded shaft, loading means connected with said shaft through a threaded member cooperable therewith, means cooperable with said shoe member upon movement of the carrier in one direction to connect the motor and threaded shaft and thereby deliver a load to the carrier and to reset said loading means upon movement of the carrier in the opposite direction.

6. In a machine of the class described, a vertically movable carrier, a driving motor therefor, means for delivering a load to the carrier, a driving connection between said loading means and the motor, spring means for disengaging said connection and means carried by the carrier for engaging said connection against said spring means.

7. In a machine of the class described, a vertically movable carrier, a motor, a controller therefor, a winding drum, a connection between said drum and said motor, a flexible element connected with the carrier and with said winding drum, a continuous flexible element having connection with the controller, brake means connected with said element, means for actuating the flexible element to control the motor and said brake means, means for delivering a load to the carrier, and a driving connection between said means and the motor, said connection being controlled by the movement of the carrier.

8. In a machine of the class described, a supporting base, a frame carried thereby, a

- drum shaft arranged within said frame, a second shaft arranged within the frame substantially normal said drum shaft, a driving connection between said shaft, means for driving said second shaft, a shaft arranged longitudinally along the machine, a driving connection between one end of said second shaft and said last named shaft, and an arresting device cooperable with the opposite end of said second shaft.
9. In a machine of the class described, a frame including a supporting base and an upright guide frame, a load carrying platform mounted for movement up and down the guide frame, means for moving the platform and means having driving connection with the platform moving means for delivering a load to the platform, said driving connection resetting the loading means after the loading operation.
10. In a machine of the class described, a frame including a supporting base and an upright guide frame, a load carrying platform mounted for movement up and down the guide frame, a driving motor for moving the platform, means having driving connection with the motor for delivering a load to the platform, said driving connection being adapted for resetting said load delivering means, and means automatically controlling said connection by the movement of the platform to impart a loading operation to said load delivering means in the downward movement of the platform and a resetting operation to said loading means in the upward movement of the platform.
11. In a machine of the class described, a frame including a supporting base and an upright guide frame, a load carrying platform mounted for movement up and down the guide frame, means for moving the load carrying platform, an arm pivoted to the carrying platform, a supporting frame and adapted for delivering a load to the platform, and a link connecting said arm with the platform moving means for operating said load delivering arm therefrom.
12. In a machine of the class described, a frame including a supporting base and an upright guide frame, a load carrying platform mounted for movement up and down the guide frame, a shaft arranged transversely across the supporting base, a pair of arms fixed on said shaft for rotation therewith and adapted for delivering a load to the platform, a pivoted arm, and a link connecting said arm and said shaft to turn same and impart a loading operation to the arms upon actuation of the pivoted arm.
13. In a machine of the class described, a frame including a supporting base and an upright guide frame, a load carrying platform mounted for movement up and down the guide frame, a continuous flexible element extending vertically along the guide frame, said element being actuated by the movement of the load carrying platform and trained over and supported by a wheel adjacent the base of the guide frame and in driving engagement with said supporting wheel to actuate same upon actuation of the flexible element, means connected with and actuated by said supporting wheel for arresting movement of the carrier, a winding drum having a flexible winding element connected between it and the platform, means for turning the drum, and a controller for said turning means supported in the path of actuation of the continuous flexible element and connected directly thereto to control the turning means by the movement of the platform.
14. In a machine of the class described, a frame including a supporting base and an upright guide frame, a load carrying platform mounted for movement up and down the guide frame, a continuous flexible element extending vertically along the guide frame, said element being actuated by the movement of the load carrying platform and trained over and supported by a wheel adjacent the base of the guide frame and in driving engagement with said supporting wheel to actuate said wheel upon actuation of the flexible element, and means connected with and actuated by said supporting wheel for arresting movement of the carrier.
15. In a machine of the class described, a frame including a supporting base and an upright guide frame, a load carrying platform mounted for movement up and down the guide frame, a continuous flexible element extending vertically along the guide frame and actuated by the movement of the load carrying platform, a winding drum having a flexible winding element connected between it and the platform, means for turning the drum, and a controller for said turning means supported in the path of actuation of the continuous flexible element and connected directly thereto to control the turning means by the movement of the platform.
16. In a machine of the class described, a load carrying platform, a yieldable stud for receiving the load upon delivery of same to the platform, and means for projecting said stud into cooperation with the load to hold same against displacement from the platform.
17. In a machine of the class described, a load carrying platform, a yieldable stud for receiving the load upon delivery of same to the platform, means for projecting said stud into cooperation with the load to hold same against displacement from the platform, and a rigid load engaging stud.
18. In a machine of the class described, a frame including a supporting base and an

upright guide frame, a continuous flexible element extending vertically along the guide frame, a load carrying platform mounted for movement up and down the guide frame 5 and having an abutment moveable along the flexible element, and an abutment on the flexible element engageable with said first abutment to control the movement of the platform, said last abutment being adjustable to permit adjustment of the point of control of the platform.

19. In a machine of the class described, a frame including a supporting base and an upright guide frame, a load carrying platform mounted for movement up and down one side of the guide frame, a generally rectangular frame on the other side of the guide frame, a power shaft for hoisting the platform, a driving sprocket on said shaft, a 15 second shaft, a sprocket on said second shaft, a driving chain trained over said first and second sprockets to transmit the driving effort of the power shaft to said second shaft, a driving member also mounted on 20 said second shaft a drum shaft journaled 25

in the generally rectangular frame and a gear mounted on the drum shaft and meshing with said driving member.

20. In a machine of the class described, a frame including a supporting base and 20 an upright guide frame, a load carrying platform mounted for movement up and down one side of the guide frame, a generally rectangular frame on the other side of the guide frame, a motor carried by the 25 main frame, a sprocket on the motor shaft, a shaft journaled in the generally rectangular frame, a sprocket on said last shaft, a driving chain trained over said first and second sprockets to transmit the driving 40 effort of the motor to said last shaft, a driving member also mounted on said last shaft, a drum shaft journaled in the generally rectangular frame, and a gear mounted on the drum shaft and meshing with said driv- 45 ing member.

In witness whereof, I hereunto subscribe my name this 21st day of December, 1921.

FRED WRIGHT.
